UNITED STATES PATENT OFFICE.

OLE SANDVOLD, OLAF RYE, AND OLAF PLATOU, OF NOTODDEN, NORWAY, ASSIGNEES
TO NORSK HYDRO-ELEKTRISK KVAELSTOFAKTIESELSKAB, OF OSLO, NORWAY.

ELECTRODE DEVICE FOR ELECTRIC FURNACES.

Application filed November 27, 1925, Serial No. 71,617, and in Norway December 27, 1924.

In electric furnaces—especially those used for the treatment of gas—it may be of importance that the air or the gas, in the furnace is under a pressure different from that of the atmosphere.

According to the present invention, it is now possible to quickly change the electrodes in such furnaces by arranging in the furnace a mediatory chamber, in which one or several electrodes can be placed. This chamber can be separated from the furnace compartment while the electrodes are fitted up, and it can be separated from the air while they are being placed in the furnace. It is not necessary to separate the whole chamber from the furnace, as it may be made to contain smaller chambers or tubes, each of which can be separated from the furnace. A construction of this kind is shown on the drawing, in which "h" is the electrode tube of the furnace. A flange "f" is fastened onto this tube, and onto this again, a chamber *a* is fastened, which is closed at the bottom by a plate "g". Two or more storage tubes *e* are placed in the chamber on a rotatable and axially movable frame in such a way that said tubes alternately come into axial alignment with the electrode tube "h". Underneath the storage tubes at the end of the electrode tube, the stave "n" can be pushed upwards to lift the electrode into the furnace. Above one of the storage tubes there is a hole "i", for the filling of the tubes with electrodes, and underneath the same tube, there is a screw "o" carrying a valve *q* whereby the tube in axial alignment with said hole can be closed both at the top and at the bottom, as it is pushed upwards towards the seat "r" which shuts it from above, whilst valve "q" shuts it at the bottom. The plug "k" can then be screwed out and the electrodes installed. After having replaced the plug and lowered the screw "o", the storage tubes can be turned round by means of the gears "c" and "v", and the crank "m", so that a new electrode comes in under the electrode tube.

Claims:

1. The combination with an electric furnace, the gas pressure in the interior of which is different from the atmospheric pressure, of a closed electrode chamber, means for introducing separate previously formed electrodes from the outside into said

closed electrode chamber and means for transferring electrodes from said closed electrode chamber to the electric furnace.

2. The combination with an electric furnace, the gas pressure in the interior of which is different from the atmospheric pressure, of a closed electrode chamber, means comprising an opening with an air-tight cover for introducing separate previously formed electrodes into the said closed electrode chamber and means for preventing communication between the interior of the electric furnace and the atmosphere during introduction of electrodes in the electrode chamber.

3. The combination with an electric furnace of a closed electrode chamber, adapted to take up two or more electrodes, means for introducing electrodes into said electrode chamber, without permitting communication between the electric furnace and the atmosphere and means for transferring electrodes from said closed electrode chamber to the electric furnace.

4. The combination with an electric furnace, the gas pressure in the interior of which is different from the atmospheric pressure, of the closed electrode chamber attached to the said furnace, an opening to the atmosphere from the said electrode chamber for introducing separate previously formed electrodes therein and an opening permitting connection between said chamber and the electric furnace.

5. The combination with an electric furnace, the gas pressure in the interior of which is different from the atmospheric pressure, of the closed electrode chamber attached to the said furnace, two or more tubes mounted on the rotatable frame inside said electrode chamber, each tube being adapted to take up an electrode, said tube being adapted by the rotation of said frame to be transferred from axial alignment with an opening for introducing electrodes into the closed chamber to alignment with an opening for transferring electrodes from the chamber to the electric furnace.

6. The combination with an electric furnace, the gas pressure in the interior of which is different from the atmospheric pressure, of the closed electrode chamber attached to the said furnace, two or more tubes mounted on a rotatable and axially movable frame, inside said electrode cham-

ber, said tubes being adapted by the rotation of said frame to be displaced from the position in alignment with an opening for introducing electrodes from outside into the closed chamber to axial alignment with another opening, for transferring electrodes from the said closed chamber to the electric furnace and means for axial displacing said tube carrying the frame so as to obtain a tight fit between the introduction opening for electrodes into the said chamber and the

tube in alignment therewith so as to prevent communication between the atmosphere and the interior of the chamber during the introduction of an electrode therein from the outside. 15

In testimony that we claim the foregoing as our invention, we have signed our names.

OLE SANDVOLD.
OLAF RYE.
OLAF PLATOU.
